UNITED STATES PATENT OFFICE

108,784

DESIGN FOR A GARMENT HANGER

Blair W. Gibson, Chicago, Ill.

Application August 27, 1937, Serial No. 71,355

Term of patent 14 years

To all whom it may concern:

Be it known that I, Blair W. Gibson, a citizen of the United States and a resident of Chicago, in the county of Cook and State of Illinois, have invented a new, original, and ornamental Design for a Garment Hanger, of which the following is a specification, reference being had to the accompanying drawing, forming part thereof.

In the drawing,

Fig. 1 is a side elevation of the garment hanger showing my design,

Fig. 2 is an end elevation of the hanger,
Fig. 3 is a bottom view of the hanger, and
Fig. 4 is an enlarged bottom view of a part of the hanger.

I claim:

The ornamental design for a garment hanger, substantially as shown.

BLAIR W. GIBSON.
